(57) **CLAIM**

The ornamental design for a mini air compressor for use in cosmetology, substantially as shown and described.

DESCRIPTION

FIG. 1 shows a top perspective view of a mini air compressor for use in cosmetology of the present invention;

FIG. 2 shows a further top perspective view of a mini air compressor for use in cosmetology of the present invention;

FIG. 3 shows a front view of a mini air compressor for use in cosmetology of the present invention;

FIG. 4 shows a back view of a mini air compressor for use in cosmetology of the present invention;

FIG. 5 shows a left side view of a mini air compressor for use in cosmetology of the present invention;

FIG. 6 shows a right side view of a mini air compressor for use in cosmetology of the present invention;

FIG. 7 shows a top view of a mini air compressor for use in cosmetology of the present invention; and,

FIG. 8 shows a bottom view of a mini air compressor for use in cosmetology of the present invention.
